UNITED STATES PATENT OFFICE.

AXEL G. J. RAPP, OF CHICAGO, ILLINOIS, AND LAURENCE M. EWELL, OF PITTSBURGH, PENNSYLVANIA, ASSIGNORS TO LINK-BELT COMPANY, A CORPORATION OF ILLINOIS.

HUTCH-VALVE-OPERATING MECHANISM.

1,395,009.

Specification of Letters Patent. Patented Oct. 25, 1921.

Application filed March 8, 1919. Serial No. 281,418.

To all whom it may concern:

Be it known that we, AXEL G. J. RAPP and LAURENCE M. EWELL, citizens of the United States, residing, respectively, at Chicago, in the county of Cook and State of Illinois, and at East Liberty, Pittsburgh, in the county of Allegheny and State of Pennsylvania, have invented a certain new and useful Improvement in Hutch-Valve-Operating Mechanism, of which the following is a specification.

Our invention relates to a hutch-valve operating mechanism for use in concentrating jigs and the like, and has for one object to provide an automatically operated and timed mechanism for periodically opening and closing the valve in the bottom of the hutch, so as to provide for the escape of sludge while preventing any unnecessary loss of water.

It is illustrated more or less diagrammatically in the accompanying drawings wherein—

Figure 1 is an end elevation of a jig partly in section with the valve mechanism installed;

Fig. 2 is a plan view of the valve operating mechanism;

Fig. 3 is a detailed section along the lines 3—3 of Fig. 2.

Fig. 4 is a detail section along the lines 4—4 of Fig. 2.

Like parts are indicated by like characters in all the figures.

A is a jig having at its bottom a valve A¹ carried on the valve rod A² which has near its upper end the lifter stop, A³ and at its top the handle A⁴.

B is a valve lifter arm rotatably mounted on rocker shaft D and having at its upper end the portion B¹ provided with the bearing surface B² and at its other end the portion B³ carrying in its end the bearing B⁴.

C is a lifting dog slotted at C¹ to admit the portion B³ of the lifter arm B upon which it is mounted, and provided with the hooked portion C² and the upper extension C³ which has on its under side the bearing surface or buffer C⁴.

D is a rocker shaft upon which is keyed the arm D¹. It has keyed to it the levers D² which have rotatably mounted between them

at their ends the pawl D³. D⁴ is a ratchet wheel rotatably mounted on the rocker shaft D, notched as at D⁵ and having one substantially deeper notch D⁶.

E is a shaft upon which is mounted a gear wheel E¹ and the crank E², to the pin E³, of which is connected one end of the connecting rod E⁴. The other end of this connecting rod is connected to the rocker arm D⁴.

F is a shaft carrying at its end the pinion F¹ which is in mesh with the gear wheel E¹. The shaft F has mounted upon it the sprocket wheel F² in mesh with the driving chain F³ which is driven by sprocket wheel G¹ mounted on driving shaft G.

H is a tripper rod secured to the frame of the jig, bent at its upper end to form the hook H¹, having at its lower point the operating surface H² adapted to strike against and depress the upper projection C³ of the lifting dog C.

I is a ratchet dog supported at I¹ on the hutch base and having the flattened end I² adapted to ride upon and engage the teeth of the ratchet D⁴.

J is a counter weight adapted to fit upon and slide along the short portion I³ of the ratchet dog I.

The use and operation of our invention are as follows:

By means of suitable gearing a rocking motion is imparted to the rocker shaft D upon which are mounted two lever arms D². These levers have between them a ratchet wheel D⁴ and the valve lifting arm B, and carry at their ends a pawl D³. As the rocker arms are rocked down, the pawl engages one of the notches in the ratchet, rotating the ratchet wheel. As they are rocked up, the pawl rides over these notches. Once in every revolution of the ratchet wheel the pawl will enter the deep notch. When it does so it penetrates sufficiently within the ratchet wheel to engage the end B¹ of the valve lifter arm, depressing it and raising its other end thereby raising the lifting dog C which engages the lifter stop 90 on the valve rod A² and thus raises the rod.

When the rod has been raised sufficiently the upper projection of the lifting dog strikes the tripper rod, and is depressed and

pushed out of engagement with the lifter stop, so that the valve rod is dropped, and the valve is thereby closed.

If more than one deep notch is used, and 5 a plurality may be desirable to give a more frequent action of the valve, then each time that a deep notch is engaged by the lever, the valve will be opened.

We claim:—

- 10 1. In a valve operating mechanism, the combination of a driving part, a power transmitting part, means for intermittently connecting them, a valve, a connection between it and said power transmitting part, 15 and means for terminating said connection after a predetermined travel of said valve.
- 20 2. In a valve operating mechanism, the combination of a driving part, a power transmitting part, means for intermittently connecting them, a valve, a connection between it and said power transmitting part, comprising a dog adapted to engage said valve, and means for terminating said connection after a predetermined travel of said 25 valve, comprising a dog tripping element.
- 30 3. In a valve operating mechanism for hatches and the like, the combination of a driving part, a power transmitting part, means for intermittently connecting them, a lifting valve, and means for intermittently connecting the power transmitting part with the valve.
- 35 4. In a valve operating mechanism for hatches and the like, the combination of a driving part, a power transmitting part, means for intermittently connecting them, a lifting valve, means for intermittently connecting the power transmitting part with the valve and means for intermittently disengaging them.
- 40 5. In a valve operating mechanism for hatches and the like, the combination of a driving part, a power transmitting part, means for connecting them, comprising a ratchet wheel and pawl, a lifting valve and means for intermittently connecting the power transmitting part with it.
- 45 6. In a valve operating mechanism for hatches and the like, the combination of a driving part, a power transmitting part, means for connecting them, comprising a ratchet wheel and pawl, a lifting valve and means for intermittently connecting the power transmitting part with it and means for intermittently disengaging the power transmitting part from it.
- 50 7. In a valve operating mechanism for hatches and the like, the combination of a driving part, a power transmitting part, means for intermittently connecting them, comprising a ratchet wheel with one or more notches substantially deeper than the others and a pawl, a lifting valve and means for connecting the transmitting part to the

valve when the pawl penetrates said deep 65 notches.

8. In a valve operating mechanism for hatches and the like, the combination of a driving part, a power transmitting part, means for connecting them, comprising a 70 ratchet wheel with one or more notches substantially deeper than the others and a pawl, a lifting valve and means for intermittently connecting the power transmitting part with it adapted to be engaged by the pawl when it 75 penetrates said deep notches.

9. In a valve operating mechanism for hatches and the like, the combination of a driving part, a power transmitting part, means for intermittently connecting them, a 80 lifting valve and means for connecting the power transmitting part with the valve, comprising a lifter dog and stop.

10. In a valve operating mechanism for hatches and the like, the combination of a 85 driving part, a power transmitting part, means for connecting them, a lifting valve and means for intermittently connecting the power transmitting part with it, comprising a lifter dog and stop, and means for intermittently disengaging the power transmitting part from it.

11. In a valve operating mechanism for hatches and the like, the combination of a driving part, a power transmitting part, 95 means for intermittently connecting them, a lifting valve, and means for intermittently connecting the power transmitting part with the valve, comprising a lifter dog and stop.

12. In a valve operating mechanism for 100 hatches and the like, the combination of a driving part, a power transmitting part, means for intermittently connecting them, a lifting valve, means for intermittently connecting a power transmitting part with the valve, comprising a lifter dog and stop, and means for intermittently disengaging them.

13. In a valve operating mechanism for hatches and the like, the combination of a driving part, a power transmitting part, 110 means for connecting them, a lifting valve and means for intermittently connecting the power transmitting part with it and means for intermittently disengaging the power transmitting part from it, comprising a 115 tripper rod, a lifter dog, and an upper extension on the lifter dog.

14. In a valve operating mechanism for hatches and the like, the combination of a driving part, a power transmitting part, 120 means for intermittently connecting them, a lifting valve, means for intermittently connecting the power transmitting part with the valve and means for intermittently disengaging them, comprising a tripper rod, a 125 lifter dog, and an upper extension on the lifter dog.

15. In a valve operating mechanism for

hutches and the like, the combination of a driving means, a power transmitting means, means for intermittently connecting them, a valve, and means for intermittently connecting the power transmitting means thereto.

16. In a valve operating mechanism, the combination of a driving part, a power transmitting part, means for intermittently connecting them, a lifting valve, and means

for intermittently lifting said valve, and separate means adapted to break said lifting connection at the end of a predetermined excursion of said lifting valve.

In testimony whereof, we have hereunto ¹⁵ set our signatures the 26th and 28th days of February, 1919, respectively.

AXEL G. J. RAPP.
LAURENCE M. EWELL.
